UNITED STATES PATENT OFFICE.

ROBERT McGREGOR, OF ILFORD, ENGLAND, ASSIGNOR, BY DIRECT AND MESNE ASSIGNMENTS, OF ONE-THIRD TO THE STIRLING BOILER COMPANY, LIMITED, OF LONDON, ENGLAND, AND TWO-THIRDS TO BABCOCK & WILCOX LIMITED, OF LONDON, ENGLAND.

WATER-TUBE BOILER OR THE LIKE.

Application filed March 14, 1922. Serial No. 543,751.

To all whom it may concern:

- Be it known that I, ROBERT McGREGOR, a subject of the King of Great Britain and Ireland, and residing at 158 Balfour Road, 5 Ilford, in the county of Essex, England, have invented certain new and useful Improvements in Water-Tube Boilers or the like, of which the following is a specification.
- 10 The present invention relates to water tube boilers of the type in which the water tubes are arranged in a bank between two headers which are connected by pipes with steam or water drums or the like. In such 15 boilers difficulty is sometimes experienced in ensuring an efficient supply of water to the lower tubes which are nearest to the fire. Further it is usual, in order to extract the maximum amount of heat from the flue 20 gases to place the tubes in staggered relation so that each tube is situated to one side of those above and below it. This necessitates the headers being made of zigzag form 25 in the case in which there is a separate header at each end of a substantially vertical row of tubes, or else requires the holes for the tubes to be drilled in staggered relation in the case in which a single header only is employed at each end of the bank.
- 30 The present invention has for its object to avoid this zigzag arrangement which entails expense and inconvenience in manufacture and upkeep, and to ensure an adequate supply of water to all the tubes.
- 35 The invention broadly consists in the improved water tube boiler hereinafter fully described and afterwards specifically defined in the appended claims.

- Two forms of the invention are illustrated 40 by way of example in the accompanying drawings, in which:—
- Figure 1 is a side view of a complete boiler, the steam and water drum being shown in section;
- 45 Figure 2 is a section on the line A—B of Figure 1, and

Figure 3 is a view similar to Figure 1 of a modification.

In the form of boiler illustrated in Figures 1 and 2 in which the steam drum 1 is placed with its axis at right angles to that of the water tubes 2, the latter are divided into upper and lower banks as indicated. In each bank the tubes are arranged, as in-

dicated in Figure 2, in a series of vertical 55 rows, these rows being arranged in mutually staggered relationship, thus ensuring the maximum extraction of heat from the flue gases in the well known manner.

It will be observed, however, that in each header or series of headers 3, the holes for the tubes 2 are drilled in a strictly vertical line, the zigzag arrangement necessary in known forms of boiler being thus avoided. The spaces occurring between the vertical 60 rows in the upper bank enables the pipes 4 connecting the lower headers 3 with the steam drum 1 to pass between the tubes of the upper bank so that no difficulty occurs in connecting the lower bank with the steam 65 and water drum.

There are thus two distinct and separate circuits for the passage of inlet water to the headers and for the discharge of steam and water from the outlet headers, thus ensuring 70 that the lower tubes are as adequately supplied with water as those above.

Figure 3 illustrates a precisely similar arrangement of water tubes 2 to that shown in Figures 1 and 2, but depicts a boiler of 75 the type in which the steam drum 1 is arranged with its axis in the same vertical plane as that of the banks of tubes 2.

It will be seen that by use of the arrangement of tubes according to this invention 80 it is possible not only to retain the straight water tubes placed in staggered relationship so as to ensure the maximum efficiency, but that in the case of the connecting tubes 4 curved portions are not necessary in order 85 to avoid the water tubes 2.

If desired, in order to secure that circulation of water from the feed water inlet 5 shall occur first through the upper bank, and then through the lower, a baffle plate 6 may 90 be fitted within the drum 1 to extend over the whole or a part of its axial length in the example shown in Figures 1 and 2, or of its width in the case of the boiler illustrated in Figure 3.

Claims:

1. In a steam boiler, an upper steam and water drum, an upper and a lower bank of horizontally inclined water tubes, upper uptake and downtake water chambers connected to the ends of the tubes of the upper bank and to said drum, lower uptake and 100 downtake water chambers connected to the

ends of the tubes of the lower bank and located between the planes of the inner faces of the upper water chambers and connections between the lower water chambers and 5 the drum, comprising tubes having imperforate walls and extending upwardly from the tops of said lower water chambers and between tubes of said upper bank and between the inner faces of said upper water 10 chambers.

2. In a steam boiler, an upper steam and water drum, an upper bank of horizontally inclined water tubes with the tubes in each vertical row thereof in vertical alignment, 15 an uptake and a downtake header connected to the ends of the tubes in each vertical row, said vertical rows being relatively widely spaced, a lower bank of horizontally inclined water tubes with the tubes thereof 20 in each vertical row thereof in vertical alignment, and each of the vertical rows of said lower bank between the vertical lines of centers of a pair of vertical rows of the upper bank, an uptake and a downtake 25 header connected to the ends of the tubes in each vertical row of the lower bank and located between the planes of the inner faces of the upper uptake and downtake headers, and tubes having imperforate walls connected 30 to the top of each of said lower uptake and downtake headers and extending through the spaces between the vertical rows of tubes of the upper bank and between the inner faces of the adjacent upper uptake and 35 downtake headers.

3. In a steam boiler, an upper steam and water drum, an upper bank of horizontally inclined water tubes with the tubes in each vertical row thereof in vertical alignment, 40 an uptake and a downtake header connected to the ends of the tubes in each vertical row, said vertical rows being relatively widely spaced, a lower bank of horizontally inclined water tubes with the tubes thereof in

each vertical row thereof in vertical alignment, and each of the vertical rows of said lower bank between the vertical lines of centers of a pair of vertical rows of the upper bank, an uptake and a downtake header connected to the ends of the tubes in each vertical row of the lower bank and located between the planes of the inner faces of the upper uptake and downtake headers, and tubes having imperforate walls connected to the top of each of said lower uptake and downtake headers and extending through the spaces between the vertical rows of tubes of the upper bank and between the inner faces of the upper uptake and 50 downtake headers and connected to said drum, said imperforate tubes being circular in cross-section and removed from the inner faces of the adjacent upper uptake and 55 downtake headers.

4. In a steam boiler, an upper steam and water drum, an upper bank of horizontally inclined tubes arranged in vertical rows with the tubes in each row in vertical alignment and said vertical rows relatively widely spaced, headers having flat sides and connected to the ends of each of said vertical rows, a lower bank of horizontally inclined tubes arranged in vertical rows with the tubes in each row in vertical alignment and with each of the rows between the vertical lines of centers of a pair of rows of the upper bank, headers having flat sides and connected to the ends of each of said vertical rows, said last-named headers being located 70 between the planes of the inner faces of the upper headers, and connections having imperforate walls between the lower headers and the drum and extending through the spaces between the vertical rows of tubes in the upper bank.

In testimony whereof I have signed my name to this specification.

ROBERT McGREGOR.
